UNITED STATES PATENT OFFICE.

HOMER O. PENCE, OF SPRING VALLEY, WISCONSIN.

OIL-PIPE CLEANER.

Application filed May 8, 1924. Serial No. 710,826.

To all whom it may concern:

Be it known that I, HOMER O. PENCE, a citizen of the United States, residing at Spring Valley, in the county of Pierce and 5 State of Wisconsin, have invented certain new and useful Improvements in Oil-Pipe Cleaners; and I do hereby declare the following to be a full, clear, and exact description of the invention, such as will enable 10 others skilled in the art to which it appertains to make and use the same.

This invention relates to an oil pipe cleaner particularly designed for use in connection with the Ford automobile.

15 It is aimed to provide a simple, inexpensive, efficient and durable construction which may be readily applied.

Another object is to provide a construction wherein an air connection with the 20 pipe is effected by means of a movable piston or tube having disaligned outlet openings to register at different times with the different portions of the pipe to concentrate the air pressure at one side or the other.

25 The more specific objects and advantages will become apparent from a consideration of the description following taken in connection with the accompanying drawings illustrating an operative embodiment.

30 In said drawings:

Figure 1 is a view partly in side elevation and partly broken away in section, of an engine as used in a Ford automobile, and which is equipped with my improvement;

35 Figure 2 is an enlarged vertical sectional view taken primarily through my improvement but showing its connection to the casing of the engine;

40 Figure 3 is a fragmentary view of the improvement in central vertical section showing the piston valve in one position, and

45 Figure 4 is a view similar to Figure 3 showing the piston valve in another position.

Like reference characters designate like or similar parts in the different views.

By way of example, an engine of a Ford automobile is shown at 10, which as usual 50 utilizes an oil pipe or tube 11 having an inlet at 12 adapted to catch oil splashed by the fly wheel and magneto 13 and to convey it to timing gearing as at 14. The casing of the engine is designated 15 and as usual has a plate at its bottom as at 16 removably closing an opening through which

access may be had with adjacent parts of the engine and particularly the tube 11. This plate is fastened in place by the usual screws or fastenings 18, which pass through 60 openings in the case 15 and a U-shaped reinforcing frame 19 inwardly of the casting and surrounding the opening 17.

In carrying out my invention, the discharge or end of the oil pipe 11 to an appropriate extent is removed as by the use of a hack saw, adjacent the timing gear 14. In place of the removed portion of the pipe 11, I provide a pipe or conduit as at 20 having an enlarged end portion 21 70 adapted to telescope over the adjacent end of the pipe 11 removably, as shown in Figure 1. Thus a passage for the oil to the timing gear 14 is reestablished.

Cast integral or otherwise provided rigid 75 with the pipe 20 is an upstanding tube 22 having its bore in communication with the bore of pipe 20. This tube or standard 22 rests on the frame 19 and is secured thereto by an elbow coupling 23.

80 This coupling 23 has a screw-threaded boss 24 which occupies the opening of one of the screws 18 and is used instead of the same. The lower portion of the tube or standard 22 is recessed and screw-threaded 85 as at 25 so as to be engaged by the boss 24 and thus clamped in place.

85 The lower end of the elbow 23 as at 26 is normally closed by a removable screw cap 27. When the cap is removed, connection may be made with a source of compressed air supply, for instance, an ordinary hand operable air pump such as is used to inflate tires may have its discharge hose 90 connected to this coupling 23.

95 The upper end portion of the standard or tube 22 is enlarged at the bore to provide a chamber 28 in which a piston tube 29 is slidably disposed. This tube is insertable 100 from the upper end which is normally closed by a removable plug 30.

105 The piston 29 has a check valve in the form of a ball 31 at its upper end to prevent flow of the oil out of its course downwardly through the standard 22. The upper end of the bore of the piston 29 is enlarged to form a cage for the ball or check valve 31 and the latter is held against upward displacement by a guard rod 32. The piston also has air outlet ports in communication with its bore as at 33 and 34 which during reciprocation of the piston are 110

adapted respectively to register with the bore of the pipe 20 to discharge air in opposite directions, as contrasted by Figures 4 and 3, respectively.

8. Piston 29 is adapted to be operated in any suitable manner as by means of a rod 35 connected thereto and passing slidably through an opening 36 in elbow 23.

10. It will be seen that the attachment may be readily applied to the pipe 11 and held in place by the elbow coupling 23 which in effect serves as the set screw 18 which it replaces.

15. In operation of the engine, the oil flows as usual through the pipe 11. In view of my improvements, it discharges into the pipe 20 and from the same engages the timing gearing at 14. Displacement of the oil downwardly into the standard 22 is prevented by the check valve 32. Should pipe 11 or 20 become clogged, cap 27 is removed, and a source of compressed air supply connected at the end 26. With the air under pressure entering the elbow 26 and standard 22, the rod 35 is reciprocated so as to register the openings 33 and 34, respectively, and alternately with the pipes 11 and 20 so that the compressed air will dislodge any obstruction. As the compressed air enters 25 but one pipe at a time, the force is concentrated in that pipe and also a series of rapidly successive blasts of air may be imparted to each pipe, thus greatly aiding in the removal of the obstruction.

30. 35. Changes may be resorted to provided they fall within the spirit and scope of the invention and it is to be borne in mind that the foregoing is merely one example of the

practice of the invention inasmuch as it is capable of use generally for cleaning oil or 40 other conduits or removing obstructions therefrom.

What is claimed is:—

1. An appliance of the class described having a pipe for connection with a conduit, a standard having a bore in communication with said pipe, said standard being adapted for connection to a source of pressure supply, and means operable through movement in the same direction to direct the pressure 50 in a plurality of directions but in a single direction at a time with respect to said pipe, consisting of a tubular member, said member having outlet ports disaligned transversely. 55

2. An appliance of the class described having a pipe for connection with a conduit, a standard having a bore in communication with said pipe, said standard being adapted for connection to a source of pressure supply, means operable through movement in the same direction to direct the pressure in a plurality of directions but in a single direction at a time with respect to said pipe 60 consisting of a tubular member, said member having outlet ports disaligned transversely, 65 an elbow secured to said standard, and an operating rod for said member slidably through said elbow.

In testimony whereof I affix my signature 70 in presence of two witnesses.

HOMER O. PENCE.
